Specification for Design.

Patented Sept. 6, 1921.

Application filed January 14, 1921. Serial No. 437,365. Term of patent 3½ years.

To all whom it may concern:

Be it known that I, FLORENCE NESMITH, a citizen of the United States, residing at Tewksbury, in the county of Middlesex and State of Massachusetts, have invented a new, original, and ornamental Design for a Garment, of which the following is a specification, reference being had to the accompanying drawing, forming part thereof.

I claim:

The ornamental design for a garment, as shown.

FLORENCE NESMITH.
